UNITED STATES PATENT OFFICE

2,489,564

APPARATUS FOR CLEARING LAND MINES
OR MINE FIELDS

Abraham Stefanus Jacobus du Toit, Transvaal,
Union of South Africa
Application August 31, 1945, Serial No. 613,812
In Great Britain March 24, 1942

Section 2, Public Law 690, August 8, 1946

5 Claims. (Cl. 89—1)

1

The present invention relates to apparatus for exploding land mines and particularly pertains to a plurality of flexible flails which are so mounted and driven as to strike the ground and detonate the explosive charges of a mine field.

An object of the present invention is to devise effective means for dealing with land mines in such a manner that they may be exploded harmlessly so that, for example, a defensive minefield may be rapidly and efficiently cleared in the sense that the mines are rendered harmless and the minefield, or a portion of the same, may thus be safely traversed by tanks or other vehicles or by infantry.

The invention consists in an attachment for a tank or other mobile unit comprising a beater device adapted to be carried in advance of the unit and to strike the ground surface and thus detonate well in advance of the unit any mine laid in the vicinity where a blow is struck.

The invention also consists in an attachment for a tank or other mobile unit comprising a rotary member or rotor carrying a plurality of chains or like flexible members disposed to strike the ground surface in advance of the unit and thus explode any mines laid in the vicinity of the points struck by the flexible members.

The invention also consists in the provision of means for varying the height above ground at which the rotary member is carried as may be required by the contour of the ground surface.

Further features of the invention will be apparent from the description given hereafter.

The accompanying drawings illustrate one mode of carrying out the invention.

Figure 1 is a side elevation, more or less diagrammatic, showing a part of a tank with one form of attachment in accordance with the invention.

Figure 2 is a plan on a somewhat larger scale of a portion of the attachment.

Figure 3 is a side view on a larger scale of a part of the attachment, looking at the opposite side from that shown in Figure 1.

Figures 4 to 6 are detail views showing one form of flexible member that may be employed.

In carrying my invention into effect in one convenient manner I form my improved mine-clearing device as an attachment to be fitted at the

2

front end of a tank *a*. In one construction the attachment comprises a substantially U-shaped frame with the limbs disposed forwardly of the tank while the base or rear end of the U member is pivoted upon the body of the tank or upon brackets carried thereby.

In the particular construction shown, the attachment consists of two channel arms *b* connected near their rear ends by cross tubes *c* which may be flanged so that the flanges may be bolted to the channels, or may be secured thereto in any other convenient manner. Welded or otherwise secured to these tubes near each end thereof is a plate *d* to which are fitted the pivot bushes on which the arms rotate, the plates being extended to form levers for a reason hereinafter explained.

At the forward end of the frame I rotatably mount a drum extending transversely of the tank and conveniently the drum is made of cage-like form so that it is not likely to be damaged by the blast from exploding mines.

In the form shown, the drum or rotor comprises a steel tube or other shaft *e* into the ends of which are welded hubs to which are secured end plates or discs *f*. To the shaft are secured four sets of arms at right angles to one another and equally spaced along the shaft. The arms are denoted by the references *gg*, *g²g³g⁴* and *g⁵* and are all tied together and to the end discs *f* by angles *h* arranged parallel to the shaft. The rotor thus described is carried in split bearings bolted to the ends of the arms *b*, the ends being slotted (as shown in Figure 1) to permit of withdrawal of the rotor.

The arms *gg²* are longer than the others (as seen clearly in Figure 3) and these carry flexible chain beaters hereafter described. In this way I form as it were a flexible beater consisting of two sets of chains extending transversely of the tank and adapted, as the drum or the cage is revolved, to beat or "flail" the ground surface well in advance of the tank and experience has shown that even with a moderate rotation of the drum of, say, 60 to 100 revolutions per minute the blows struck by the chains will be sufficient to detonate any mines laid in the vicinity of the points where such blows are struck even though these mines may be buried a relatively considerable distance below the actual ground surface.

In the construction shown, two sets of chain beaters are provided, but it will be understood that any other number of sets may be chosen, and where there are more than one set, the beaters of one row may be staggered in relation to another to give greater striking cover to the ground. The form of the flexible beaters and the manner of attaching them to the rotor may be variously modified, but in order to give good visibility to the driver of the vehicle while at the same time affording a high degree of lateral stability to ensure good ground cover by maintaining the chains in position, I prefer the arrangement seen most clearly in Figure 2. In this construction, the arms gg^2 have attached to them, a series of links i attached by T-pieces to two tubes kk' , the adjacent ends of which are chamfered, as shown, to allow freedom of movement in one direction. The chains l are attached to the tubes by swivels l' located between collars l^2 , the swivels preventing the chains from coiling themselves round the tubes.

The form of chain which has been found very satisfactory in practice is that shown in Figures 5 to 7 and consists of the chain l reinforced for half its length by two steel wire ropes mn (one only being shown in Figure 7 for clearness) threaded through two adjacent links next to the end links which are attached to the tube k or k' . The cables are threaded through diagonally and are clipped to the chain at intervals by the clips o and cross bolt o' . The free ends of each cable are united by a steel or other sleeve p into which they are soldered.

The drum or cage may be rotated either from the tank motor or from one of the track sprockets thereof or preferably as shown from a separate motor q disposed in a housing at the side of the tank, and the drive in any case may be by way of a propeller shaft r and worm and worm wheel r' , or by chains and sprockets or by other suitable means but the propeller shaft drive is preferred for obvious reasons. Also the propeller shaft is preferably enclosed in a suitable casing. A torque rod r^2 may connect the housing of the worm and worm wheel to the adjacent arm b . If desired, I may employ duplicate drives, one to each end of the drum, and with a separate engine for each drive.

It will be clear that when the vehicle is moving over ground surface the contour of which is changing, the height of the drum or cage rotor may require to be changed from time to time in order that the chains or flexible members may strike the ground surface properly and this is conveniently effected by means of hydraulic jacks s carried at the sides of the tank and operating upon arms or levers constituted by the extensions of the plates d secured to the pivots of the frame so that the inclination of the latter may be varied as required and as shown by the dotted lines in Figure 1. In this connection it will be understood that the controls for the drive and for the adjustment of the elevation of the rotary device are located inside the tank so as to be operable from within.

From the foregoing description it will be seen that I have provided a simple form of attachment for a mobile unit which is so constructed as to be liable to little or no damage from blast of exploding mines and which is under the control of an operator protected from such blast, and at the same time the device is such that it will successively detonate all mines buried in the path or track taken by the vehicle. Thus I am able com-

pletely to clear a path through a minefield which may be safely traversed by following vehicles or infantry and the extent of the area cleared may be varied by varying the width of the attachment and/or by using a number of the same carried by vehicles taking different paths or tracks.

The invention is not to be limited to the foregoing details which are given by way of example only as I may modify the form of beaters and the means by which they are carried and driven depending upon any practical requirements; for example, the chains may be replaced by lengths of cable or I may employ spring arms or other suitable flexible members and in some cases particularly when employing chains the device may be rendered more effective by attaching a ball at the end of each of the chains.

I claim:

1. A device for exploding land mines comprising a shaft, means supporting the shaft above the ground and for movement on a given path of travel, means rotating the shaft in the course of its movement on such path, and flexibly jointed flails attached to the shaft and of such a length so that as the shaft rotates the flails strike the ground in advance of the shaft.

2. A device for exploding land mines comprising, a shaft, means supporting the shaft above the ground and for movement on a given path of travel, means rotating the shaft in the course of its movement on said path, flexibly jointed flails attached to the shaft and of such a length that as the shaft rotates the flails strike the ground in advance of the shaft, and means for adjusting the position of the shaft with reference to the ground.

3. A sweeper for land mines comprising, frame arms provided with pivotal mountings for connection with a propelling vehicle, said arms being disposed to extend forwardly of the vehicle, a shaft extending transversely between the arms and mounted for rotation on said arms, chains attached to the shaft, means including a prime mover provided with driving connections for the actuation of said shaft at a speed to distend the respective chains circumferentially, and the length of said chains exceeding the height of the shaft from the surface traversed whereby the chains will flail such surface in advance of the movement of the shaft.

4. Apparatus for detonating land mines comprising, a propelled vehicle, a pair of spaced arms mounted on and extending forwardly from said vehicle, a cage-like drum arranged transversely of the arms and supported for rotation on said arms, means for rotating said drum, and flexible members connected to said drum of such lengths as to engage the ground in advance of the drum as the drum is rotated.

5. Apparatus for detonating land mines comprising, a propelled vehicle, a pair of spaced arms mounted on and extending forwardly from said vehicle, a cage-like drum arranged transversely of the arms and supported for rotation on said arms, means for rotating said drum, flexible members connected to said drum and of such lengths as to engage the ground in advance of the drum as the drum is rotated, and hydraulic actuated means for adjusting the position of the forward ends of said arms and the drum above the ground.

ABRAHAM STEFANUS JACOBUS DU TOIT.
